UNITED STATES PATENT OFFICE.

OLIVER R. NELSON, OF CHICAGO, ILLINOIS.

OIL-PRESS MAT.

SPECIFICATION forming part of Letters Patent No. 349,515, dated September 21, 1886.

Application filed February 18, 1886. Serial No. 192,326. (No model.)

To all whom it may concern:

Be it known that I, OLIVER R. NELSON, of Chicago, in the county of Cook and State of Illinois, have invented certain new and useful 5 Improvements in Oil-Presses; and I do hereby declare that the following is a full, clear, and exact description thereof, reference being had to the accompanying drawings, and to the letters of reference marked thereon, which form a 10 part of this specification.

This invention relates to oil-presses in which absorbent mats are employed in contact with the bag of meal to be pressed; and it has among its objects to provide improved features of construction in such presses and presses of analogous character, first, whereby the destructive effects of strain upon the absorbent mats, and upon the duck press-cloth or wrappers for the meal may be obviated, and, second, whereby 15 an increase of the capacity of the press may be obtained by the omission of one and the retention of one of the absorbent mats, and at the same time the adhesion of the meal to the metal surface with which it is thus brought in 20 contact is avoided.

To these and other ends my improvements consist in the matters hereinafter set forth, and pointed out in the appended claims.

In the accompanying drawings, Figure 1 is 25 a perspective view of a press-plate of an oil-press having certain forms of my improvements applied thereto. Fig. 2 is an under side view of an absorbent mat having a reticulated plate of metal attached thereto; which plate, when resting on the press-plate, presents a 30 surface having prominences or projections which are relatively stationary and which enter or embed themselves in the mat. Fig. 3 is a fragmentary perspective view of a sheet-metal 35 plate intended to be applied to the surface of a press-plate and having a sheet of asbestos paper or other non-conducting substance applied to the under surface thereof, so that the latter will be interposed between the press-plate and metal sheet. Fig. 4 shows a fragment 40 of a similar sheet of metal plate for the same position folded at the edge to form the "selvage," the asbestos sheet in this figure being omitted. Fig. 5 is a perspective of fragments of press-plates, showing two forms of 45 prominences or projections upon the surface of the plate, which, in connection with a pene-

trable mat, serve the same purpose as the surface inequalities of the wire-netting shown in Fig. 2. Fig. 6 shows a press-plate of the character separately shown in Fig. 5, but having the projections on its lower surface only and a penetrable mat attached to that surface, while the upper surface of the press-plate is equipped with a smooth-surfaced sheet-metal plate of 55 the character represented in Fig. 4.

A represents one of the series of press-plates of a linseed or other oil-press having longitudinal troughs *a* along its lower margins for the conduct of the expressed oil to the delivery 60 side of the press.

B is an absorbent mat fabricated of hair or other suitable material.

C is a sheet of wire cloth or netting corresponding in size, preferably, very nearly with 70 that of the mat B.

D is a thin sheet-metal plate having a smooth surface, preferably Russia iron.

E is a sheet or body of asbestos or other non-conductor of heat interposed between the 75 plate D and the press-plate A.

F are fastenings, either of the usual twine or wire or of other form, by which the plate D or mat B may be secured to the press-plate.

It is well known that in the use of oil-presses the ground meal from which the oil is to be pressed is formed in a flat rectangular mass inclosed upon its upper, lower, and end surfaces by ducking or wool cloth folded about it. This body or cake of meal thus inclosed 80 is inserted between two adjacent plates, A, of a hydraulic press, and is then subjected to a pressure commonly reaching four thousand pounds to the square inch. Both proximate faces of each pair of plates have commonly 85 been provided with hair mats B, about three-fourths of an inch in thickness, and adapted by a degree of compressibility to compensate for any inequality in the density of the cake or block of meal, and also adapted to absorb 90 a quantity of oil. In the use of the press these mats, strong as they are, frequently break apart after some time, and the duck covering of the cakes, or press-cloth, is also very soon 95 ruptured and rendered useless. I have decided that these results are due to the lateral expansion of the mats under the heavy pressure referred to. To remedy this action I have 100 provided a means for preventing the expansion

sion of the mats, and find, as a result, that both the mats and the press-cloths are rendered far more durable, and that the mats, in fact, are made practicably indestructible. The device for this purpose is herein illustrated in two forms in Figs. 1, 2, and 5. In Figs. 1 and 2 it is in the form of a sheet of wire-netting placed in contact with the mat, so that under the pressure of the press the wires embed themselves at short intervals in the penetrable body of the mat. The intersected wires of the netting present prominences which by their connection in the sheet are relatively immovable, and which, by their engagement with the mat effectually prevent the latter from stretching. This wire-netting may advantageously rest directly upon or in contact with the press-plate, so as to form essentially an uneven surface of the latter, and the interposition of any body between the wire-cloth and plate (as a part of a mat or of a double mat) will not change this essential character and operation of the netting as described, or be a departure from my invention.

In Figs. 5, 6, and 7 the prominences which engage the mat are formed directly upon the surface of and are integral with the press-plate. At the left in Fig. 5 and in Fig. 6 such prominences are in the form of rounded studs a' , and at the right in Fig. 5 and in Fig. 7 the prominences a' are pyramidal and formed by cutting intersecting V-grooves in the surface of the patterns from which the plates are cast. The prominences a' being numerous, and, like those of the wire-netting, not far apart, are each subjected to only slight lateral strain under the tendency of the mat to stretch, and consequently together easily hold the mat from slipping at all points and prevent its elongation or lateral expansion.

Two heavy mats between adjacent press-plates obviously occupy considerable of the space of the press. To increase the capacity of the press, cast-metal plates have heretofore been substituted for both mats, but at a sacrifice, of course, of all the advantages of the absorbent qualities of the mats. It has also been a serious objection to these plates that the meal would be squeezed through the press-cloth and would adhere to the plate, preventing the ready removal of the oil-cake and also injuring the cloth. I propose to enlarge the capacity of the press, and at the same time to retain the advantage of the mat, by dispensing with only one of the latter, and remedy the defect of adhesion by employing a thin smooth-surfaced metal plate, D, preferably of Russia sheet-iron, to which it is found that the meal will not adhere. The immunity from sticking is in some degree further increased by interposing a thin sheet of asbestos or other thin body of non-conducting material between the plate D and the press-plate. The asbestos or other non-conductor serves still another purpose in preventing the temperature of the cake from being lowered by proximity to the press-plate, and thus preserves its outer sur-

face in better condition for the expression of the oil.

The desired selvage or thicker margin of 70 the sheet-metal plate D may be produced by folding its edges under in as many folds as may be necessary, or by the introduction of one or more thicknesses of metal or other material beneath the margins of the plate or 75 within a marginal fold thereof. In Figs. 1, 2, and 6 the plate D has only a single fold; in Fig. 4 it has a double fold, and in Fig. 3 a folded piece of duck or other material is included with the edge of the asbestos sheet E, 80 within the fold of the plate. In Figs. 1 and 2 the mat B is thickened or raised at its margin by an under fold of the wire-cloth C. The special provision of this selvage or greater marginal thickness of the mat or plate is required 85 in all presses having plates A of uniform thickness.

In Figs. 5 and 6 I have shown a construction of the press-plate in which its greater thickness at the margins obviates the thickening of the edges of the mats B and plates D. The concavity of the press-plate here shown may be sufficient to wholly attain the object of confining the cake laterally, or additional concavity of the outer surface of the mat or 95 plate D may be obtained, as indicated, by the usual selvage or other thickening of the margins of these plates.

The mats and smooth plates, together with the underlying parts, if present, may be secured to the press-plates by the usual devices of twine or wire ties, (seen at F, Fig. 1,) or in the case of the plates D screws may be used, as suggested in Figs. 3, 4, and 6.

When a single mat B and plate D are used 105 in opposition to each other in the space between two adjacent press-plates, either the mat or the plate D may be the upper or the lower; but I prefer to employ the mat below the meal-cake or upon the upper surface of 110 the press-plate, and the metal plate D on the opposite side of the meal-cake.

I am aware that it has been proposed to employ press-plates having corrugated surfaces and also projections on the surfaces of 115 press-plates, to be used without absorbent mats and directly in contact with the meal-bag. This is not my invention, which expressly proposes the use of the absorbent mat, and which, in fact, has for its express object 120 the preservation of such mats from injury, in order that their advantages may be profitably utilized.

I am also aware that wire mats have been proposed containing an absorbent interior 125 layer or body. This is also not my invention, which, on the other hand, seeks to preserve the well-known advantages of using an absorbent mat in direct contact with the meal-bag, while at the same time preventing the destruction of such a mat. The great cost of these mats—commonly about six dollars each—and their rapid destruction as heretofore employed, makes their better preservation im-

portant as affecting the cost or profit of oil manufacture. The wire mat above referred to does not present the absorbent body next to the meal-bag, and therefore, while durable, lacks the advantage of the usual mat. To attain the ends desired, the present invention therefore proposes to employ a reticulated wire fabric on the under side only of the mat or between the mat and the press-plate, and to the claim relating to this construction is limited to the arrangement stated.

I am further aware that sheet-metal plates have been employed or proposed as a covering for both adjacent faces of a hinged two-part mat, the bodies of the hinged parts of which are built up of layers of paper. This is not my invention. My said invention, relating to this smooth-surfaced plate, is expressly limited to the combinations stated in claims 3 and 4. In the construction of claim 4 the advantages of the absorbent mat used in direct contact with the meal-bag are retained, and the capacity of the press, which is greatly taken up by such mats when two are used, is materially increased, while, by the provision of a smooth surface on the added metal plate, the adhesion of the bag to the metal is prevented.

I claim as my invention—

30 1. The combination, with a press-plate provided with projections upon its surface, of a

penetrable absorbent mat resting on said surface and adapted to be penetrated by such projections, substantially as and for the purpose set forth.

35

2. In combination with a penetrable and absorbent mat and a press-plate, a sheet of wire netting interposed between the mat and the press-plate, the opposite surface of the absorbent mat being uncovered and exposed 40 directly to the meal-bag in the use of the press, substantially as described.

3. The combination, with a cast press-plate of an oil-press, of a separate sheet of smooth-surfaced metal secured to said press-plate, and 45 a non-conducting substance interposed between said sheet and press-plate, substantially as described.

4. In combination with two adjacent press-plates, an absorbent mat applied to one of the 50 two proximate faces of said plates and exposed directly to the bag of meal to be pressed, and a separate smooth-surfaced metal sheet secured to the other of said proximate faces of the plates, substantially as described.

55

In testimony that I claim the foregoing as my invention I affix my signature in presence of two witnesses.

OLIVER R. NELSON.
